Aurelius Steward.

UNITED STATES PATENT OFFICE.

AURELIUS STEWARD, OF BRIDGEPORT, CONNECTICUT, ASSIGNOR TO THE WHEELER & WILSON MANUFACTURING COMPANY, OF SAME PLACE.

PLAIT-FOLDER FOR SEWING-MACHINES.

SPECIFICATION forming part of Letters Patent No. 233,380, dated October 19, 1880.

Application filed June 5, 1880. (No model.)

To all whom it may concern:

Be it known that I, A. STEWARD, a citizen of the United States, residing at Bridgeport, in the county of Fairfield and State of Connecticut, have invented certain new and useful Improvements in Plait-Folders for Sewing-Machines, of which the following is a specification.

The object of my invention is to automatically fold the fabric into a plait or tuck as the fold is being stitched down, and to govern the width of said folds and control their distances apart with greater convenience and regularity than has heretofore been accomplished.

In the accompanying drawings, Figure 1 shows the tuck-folder in perspective, together with part of the table, bed-plate, needle-bar, and presser-bar of a sewing-machine. Fig. 2 shows, partly in section, an end and enlarged view of the parts which form the folds; and Fig. 3 shows, also partly in section, the same parts with cloth inserted as in the act of being folded and stitched.

In this form of plaiting or tucking the material is so folded that three plies are overlapped, as seen at A, Fig. 3, which represents an edge view of the material, the line of stitching being near one edge of the overlapping portions. To form these folds the material is passed between two metal plates, which I term "fold-guides," the overlapping edges of which serve to keep the folds in proper position, the upper fold-guide being attached adjustably to the bed-plate, and the lower fold-guide connected, directly or indirectly, with the arm of the sewing-machine.

In the case represented in the accompanying drawings the lower fold-guide is constructed of thin flexible metal, shaped as shown at B, Fig. 1, and secured firmly by soldering or otherwise to the presser-foot C, that portion which is attached to the foot being bent in concave form to render it rigid in the required direction, the edge which enters the fold in the cloth being made somewhat thicker by folding over the metal or otherwise to form a smooth edge over which the cloth will pass freely, the front end being rounded off, that it may not turn the fold too abruptly, and the whole so set as to

height that when the presser-foot is down all 50 that portion which stands in front of the same may press lightly upon the material which is being sewed.

The upper fold-guide, D, is constructed as seen in Fig. 1, and connected by means of a 55 hinge to the sliding plate E, the sliding plate being held to the bed-plate of the sewing-machine by means of the thumb-screw F. In this view the fold-guide D is shown as when opened for the introduction of the material, as hereinafter described.

Below the sliding plate E is placed a base-plate, G, upon a portion of which, within a slot in the sliding plate E, is stamped an index, and upon the front end of the same is 65 formed an auxiliary guide, (shown at H.) The base-plate G is also held in position by the thumb-screw F, which passes through a closely-fitting hole in the base-plate to keep it always in one position.

To the presser-foot C, by means of the adjusting-screw K, I attach the space-guide L, it being composed of thin metal, with the portion through which the screw passes bent in concave form, and its edges turned at right angles 75 to give it the necessary rigidity, while the extending portion remains flexible and yielding to accommodate itself readily to inequalities in the cloth.

The operation of my invention is as follows: 80 The presser-foot being raised, the fabric is placed beneath the lower fold-guide, B, and the space-guide L, and the front edge carried forward to the presser-foot. The upper fold-guide, D, is then folded over the lower one, 85 carrying with it a fold of the fabric, the presser-foot let down upon the fold, and the fold stitched down in the usual manner.

The sliding plate E, which is slotted for that purpose, may, by loosening the thumb-screw 90 F, be moved to the right or left, causing the upper to overlap the lower fold-guide to a greater or less extent, thereby governing the width of the tucks.

When in use the fold-guide D rests upon the 95 auxiliary guide H, and though the former may be adjusted for the purpose stated, the latter always remains in close proximity to and

serves to form the lower fold around the edge of the guide B. The edge of the fabric or the preceding tuck is in each case passed over the protruding lip and guided by the edge of the space-guide L, and by setting the latter by means of its adjusting-screw K any desired space between the tucks may be obtained.

As the index is stamped upon the base-plate, which remains stationary, the sliding plate, carrying the upper fold-guide, D, and the space-guide L may each be regulated by the index to give the width and space desired.

It will readily be seen that the hinging of the upper fold-guide, D, greatly facilitates the introduction of the material, and that by connecting the lower fold-guide with the arm the device does not obstruct the passage of the work, the number of folds which may be made

in succession being limited only by the space under the arm of the sewing-machine.

What I claim as my invention, and desire to secure by Letters Patent, is—

1. The combination of the lower fold-guide, B, the upper fold-guide, D, the sliding plate E, the base-plate G, and the auxiliary guide H, all constructed and operating substantially as specified.

2. The combination of the upper fold-guide, D, the sliding plate E, the base-plate G, and the auxiliary guide H, all constructed and operating substantially as described.

AURELIUS STEWARD.
